CONVECTION CURRENT REFRIGERATOR

George Oscar Rudolph Lindgren, Galesburg, Ill., assignor to Outboard, Marine and Manufacturing Company, Waukegan, Ill., a corporation of Delaware

Application February 21, 1941, Serial No. 379,955

12 Claims. (Cl. 62—89)

My invention relates to improvements in refrigerators, with particular reference to refrigerators of a domestic type employing gravity circulation of convection currents in a cyclic path or paths including a chilling unit and one or more food storage chambers enveloped by such currents.

My object is to provide an improved refrigerator of the described type, in which food materials may be stored at different temperatures and protected against dehydration in cases where such protection is desired, and in which the desired temperatures in different zones or chambers may be accurately maintained by convection currents dependent upon gravity circulation.

More particularly, my objects are to provide a refrigerator cabinet with a set of storage chambers assembled within the cabinet in spaced relation to some of the walls thereof in such a manner as to provide means for accurately maintaining selective temperatures within the respective chambers through gravity circulation of convection currents; to provide means whereby storage chambers intended to be kept at low temperatures may be associated with a chilling unit in one compartment of a cabinet and the convection current or currents controlled as to direction of flow in such a manner as to cause them to circulate by gravity along well defined paths and in sheet-like currents enveloping the exterior surfaces of one or more chambers located in zones or compartments remote from the chilling unit, and in which higher temperatures are desirable, to provide spacing means for not only separating one or more storage chambers from the insulated walls of the cabinet, but for directing the convection currents along said defined paths of circulation; to utilize some of the spacing devices as sealing means for excluding the convection currents from the interior of the chamber or chambers which they envelop; and in general to provide means whereby the development of eddies, counter-currents and dead spots may be avoided and circulation accelerated in a manner to promote uniformity in the maintenance of the desired temperatures in all parts of the refrigerator.

In the drawings:

Figure 1 is a front elevation of a refrigerator embodying my invention, with parts broken away to disclose constructional details.

Figure 2 is an elevational section, drawn to line 2—2 of Figure 1.

Figure 3 is a view, partly in elevation and partly in section, drawn to line 3—3 of Figure 2. 55

Figure 4 is a plan view, in partial section, of the device shown in Figure 3, taken along line 4—4.

Figure 5 is a plan view, in partial section, along line 5—5 of Figure 3.

Figure 6 is a plan view of an alternate embodiment of the invention, showing the top wall removed to disclose the evaporator unit construction.

Figure 7 is a vertical section of the upper portion of the refrigerator shown in Figure 6, taken along line 7—7.

Figure 8 is a front elevation of the refrigerator shown in Figure 6, with the freezing compartment door removed.

15 Like parts are identified by the same reference characters throughout the specification and drawings, and in the modification the corresponding parts are identified by the same numbers with a reference letter added. Various other 20 modifications are contemplated, and nothing in the description or drawings is intended to imply any limitation of the scope of the invention as defined in the respective claims.

In Figures 1 to 5, inclusive, I have illustrated 25 a refrigerator of the domestic type having a cabinet provided with a lower compartment 10 for the motor and compressor, an intermediate compartment 11 which houses a storage chamber, and an upper compartment 12 which houses 30 a chilling unit and one or more chambers for meat and other foods requiring low temperatures for prolonged preservation. The walls of the compartments 11 and 12 are insulated, any ordinary insulation being used as indicated at 13.

35 The compartment 12 has a non-corrosive lining 14, preferably of metal or porcelain, and its bottom wall has slots 15 and 16 along its side and rear margins (Figure 4). Said bottom wall otherwise serves as a partition between the compartments 11 and 12, both of which have doorway 40 openings at the front which may be closed by a single door 17, although it is immaterial to the invention herein disclosed whether the compartments have separate doors or whether they are 45 both closed by a single door.

A food storage chamber 18, open at the front, is mounted in the compartment 11, from the walls of which it is spaced by chamber supporting and current controlling bars 19, sealing bars 20, and vertical current controlling bars 21 and 22. The sealing bars 20 extend along the front margins of the bottom, side and top walls of the storage chamber 18 and may be hermetically sealed to these walls and to the walls of the

cabinet to prevent access of the convection current to the interior of the chamber.

The vertical bars 21 and 22 subdivide the space which they occupy into thin relatively wide passages, through which the convection currents may be guided in the form of chamber enveloping sheets. In the construction shown, the currents which flow downwardly between the vertical sealing bars 20 and the middle bars 21 at the respective sides of the cabinet are directed inwardly underneath the bottom of the chamber 18 between the bottom sealing bar 20 and the inwardly extending legs of the supporting bars 19, and are then guided by the rearwardly extending legs of the supporting bars 19 to the rear passages between the vertical spacing bars 22, as shown by the arrows in Figure 5. The currents which descend along the sides of the chamber 18 between the middle and rear side bars 21 are guided into the rear passages across the bottom corner spaces defined by the bars 19. The number of spacing and guiding bars to be employed will depend upon the size of the refrigerator.

The width of the respective convection currents is sufficiently limited by these bars to prevent the development of eddies, counter-currents or dead spots, to an extent which would otherwise impair the efficiency of the refrigerator or the uniformity of the temperature in the chamber which these currents envelop.

The top of the chamber 18 is covered by an insulating slab 23 from which the lining 14 of compartment 12 is supported by spacing bars or strips 24, preferably of the same L shape or angular form as the bars 19 in Figure 3. The space between the bottom of the lining 14 and the slab 23 is in communication with the above mentioned passages, as best shown in Figure 4, so that the currents across the top of the food chamber 18 are the exact opposite of the currents across the bottom (see arrows in Figure 3 and Figure 4, respectively).

As shown in Figure 1, the chilling unit is located midway between the side walls of compartment 12. It includes a quick freezing chamber 28 open at the front and encircled by a helically wound evaporator coil 29 of ordinary type, and it is flanked by chambers 30 and 31, also open at the front, and adapted to receive various food, such as are usually kept at low temperatures. The chamber 28 and one or both of chambers 31 and 30 may be normally closed by a shutter or door 32 to prevent complete change of air in the convection system when the main door 17 is open, assuming that a single door 17 is used for both compartments. The openings at 15 and 16 permit the convection currents to circulate in part into and out of chamber 12 in shunt respecting the circulation paths shown in Figure 4.

Air flows across the top of the chilling unit in the direction of the sides of the compartment, being guided to some extent by the evaporator coils. It descends by gravity through the slots 15 into the channels between the spacing bars 20 and 21, and then passes underneath the chamber 18 to the back wall channels in the manner above described.

In the back wall channels a portion of the air passes upwardly through the slots 16 into the compartment 12, where it flows forwardly over the chilling unit and the associated storage chambers and then divides and again flows downwardly along the sides of the compartment through the slots 15. The slots 15 are longer

than the slots 16, or otherwise made of greater capacity. There are two slots 15 on each side and four slots 16 along the back wall. Since the slots 16 are of less capacity, some of the returning air is deflected forwardly over the slab 23 and guided by the spacing bars 24 to the respective side channels to be mingled with the descending currents. The bars 24 are similar in form to the bars 19 and therefore keep the deflected air subdivided for substantially equal delivery into the descending streams.

In the embodiment illustrated in Figures 6, 7 and 8, the compartment 12a contains two quick freezing chambers 28a and 28b, one on each side of a central storage chamber 30a. An evaporator coil 28a is wound a plurality of turns on the chamber 28a and then extended, as indicated at 50, over the storage chamber 30a, to be wound a plurality of turns upon the freezing chamber 28b and then extended under the storage chamber 28a, the windings upon the respective freezing chambers being thus alternated throughout their length.

In this construction the two freezing chambers and their coils are located in close proximity to the side walls of the cabinet, thereby not only separately chilling the currents descending along their respective side walls, but more efficiently dividing the air above these coils and above the chamber 30a into two cyclic streams descending along the respective sides of the refrigerator. The rate of circulation may thus be increased over that prevailing in the structure shown in Figure 1.

Also, in this modified construction the forward margins of the quick freezing chambers and those of the storage chamber 30a are sealed to each other and to the compartment lining 14 by sealing strips 55. These sealing strips have their outer margins connected with the margins of the lining wall 14 around the main doorway opening, thus not only excluding the convection currents from the chambers, but also preventing air from entering the passages when the main door is opened.

It will be noted that in each of the constructions illustrated the quick freezing chambers and associated storage chambers have their longitudinal axes extending from front to rear, and the evaporator coils therefore tend to guide the convection currents laterally. The entire weight of the inner wall or lining of the compartment 12 is not wholly carried upon the spacing bars 24 but is marginally supported by the vertical sealing and guide bars 20, 21 and 22. Therefore the descending currents are maintained in well defined paths by the guide bars at all points, thus assuring the complete and uniform cooling of all side walls of the storage chamber 18. The subdivided streams may be allowed to commingle during the return flow, as shown, if desired.

If will be noted that the back wall of the cabinet is provided with a removable section 59 which facilitates installation of the liner 14 with the chilling unit and its associated chambers installed therein. The back wall section 59 has a cavity for reception of an ordinary expansion valve, conventionally indicated at 60, and which may, if desired, be used to control deliveries to the evaporator tube, the inlet end 62 of which is shown in Figure 2 as extending through the wall of the liner 14. A casing 61 extending vertically along the rear wall of the cabinet may house the supply and return connections between the evap-

orator coil and a condenser compressor assembly in the lower chamber 10.

In the construction shown, the main door 17 may, if desired, be used to seal all of the chambers in compartment 12 when this door is closed.

In each of the constructions illustrated there will be air currents in the food chamber 18, created by temperature differentials between different wall portions thereof according as such wall portions are contacted by the colder or warmer portions of the circulating convection currents. Therefore the air currents in the food chamber 18 will tend to follow the same direction as the air currents externally of chamber 18, and will be equally well distributed throughout the food chamber. At the same time the food in chamber 18 will retain its moisture, for the reason that the air circulating in that chamber is nowhere exposed to any surface which has temperatures below the freezing point of water and hence would not tend to accumulate frost. The elimination of the dehydrating effect from the main food storage chamber is a very important and desirable characteristic of the improved structure, and it is significant that in the present device this result is secured while still maintaining the desirable and effective distribution of well established currents of convection air circulation within the chamber.

It is also important that in my improved structures multiple temperatures are attained in a very economical and simple manner without requiring multiple temperature evaporator coils or separate temperature controls.

While my drawings show a complete liner immediately within the insulation 13 for the purpose of protecting such installation from moisture, it will be understood that in the preferred arrangements, whereby the air or other gases circulating as convection currents are completely hermetically sealed within the convection space, no accumulations of moisture are ordinarily possible, and this additional liner may be omitted where it is unnecessary.

I claim:

1. In a refrigerator, the combination of a heat insulated cabinet having a food chamber disposed therein and spaced from the cabinet walls to permit circulation of convection currents along the side and back walls of the chamber, a chilling unit compartment fitted within the cabinet above the food chamber and having a bottom wall provided with apertures along its side and rear margins to allow communication between the chilling unit compartment and the space surrounding the food chamber, means for subdividing and directing convection currents in thin streams of definite width downwardly from the chilling unit compartment along the sides of the food chamber and underneath its bottom to the space between the food chamber and the back wall of the cabinet, said back wall space allowing a return flow to the chilling unit compartment, and guide strips between the bottom wall of the chilling unit compartment and the top of the food chamber defining horizontal passageways therebetween, said guide strips having portions extending from said back wall space forwardly and laterally for directing portions of the currents ascending along the back wall to the streams descending along the sides of the food chamber.

2. A refrigerator cabinet, having in combination a set of superposed compartments, a food storage chamber in the lower compartment spaced from the top, side, bottom and rear walls there-

of by current directing guide strips subdividing said space into passages for convection currents, a chilling unit in the upper compartment, and sealing strips confining the convection currents to the upper compartment and said passages, the bottom wall of said upper compartment having marginal openings along its side and rear portions in registry with the respective passageways at the sides and rear of the food storage chamber, the rear openings being of less capacity than those at the sides, and each rear passage having a by-pass connection with a side passage through one of the top passages, whereby portions of the return flow may be passed over the chilling unit and other portions by-passed while maintaining substantially equal distribution and temperature regulation about the storage chamber.

3. In a refrigerator as set forth in claim 2, a chilling unit provided with transversely extending refrigerator coils adapted to aid in directing the chilled convection currents downwardly in said side passages.

4. A refrigerator cabinet having superposed compartments separated by a wall having slot-like openings along its side and rear margins, a chilling unit in the upper compartment adapted to deliver convection currents in substantially equal volume downwardly through the openings along the side margins of said wall, a food storage chamber in the lower compartment, separated from its top, side, bottom and rear walls by spacing strips adapted to subdivide the space which they occupy into passages and thereby maintain substantially uniform distribution of said convection currents, the top and bottom spacing strips extending inwardly from the respective side walls of the cabinet and rearwardly toward intermediate portions of the rear wall of the storage chamber, said chilling unit chamber and the passages with which it communicates being sealed for permanent retention of the convection currents.

5. The combination with a refrigerator cabinet having a front door and side, back, top and bottom walls, of a food chamber connected to said cabinet about said door and having side, back, top and bottom walls spaced from the corresponding walls of the cabinet, a chilling unit within the cabinet in the space between the top wall of the cabinet and the top wall of the food chamber, and supporting and spacing means positioning the food chamber within the cabinet and defining passageways for the circulation of convection currents upon predetermined paths about the food chamber, said spacing means comprising substantially upright guides between the respective side walls of the food chamber and cabinet, and guides between the bottom walls of the food chamber and cabinet extending inwardly and rearwardly from the guides first mentioned, whereby convection currents descending along the side walls of the food chamber and separated by said guides will be directed upon different paths across the bottom of the food chamber and toward the back thereof, the space between the back walls of the food chamber and cabinet providing a return passageway for ascending convection currents communicating with currents moving at both sides of the respective bottom guides, whereby such currents are merged during their return in the last mentioned passageway.

6. In a refrigerator, a cabinet comprising top, bottom, side and back walls and a front door, supporting guides extending inwardly and rearwardly from intermediate portions of the respec-

tive side walls across the bottom wall of the cabinet and toward the rear wall thereof, lateral guides upright against the side walls of the cabinet and substantially contacting the respective supporting guides, a food chamber having a bottom wall resting upon the supporting guides for spacing from the bottom wall of the cabinet and having side walls laterally contiguous to the lateral guides and spaced thereby from the side walls of the cabinet, said food chamber having a back wall spaced from the back of the cabinet and a top wall remote from the top wall of the cabinet, top guides upon the top wall of the food chamber corresponding in general location to the supporting guides therebeneath and extending inwardly and rearwardly from said lateral guides, means spacing the rear wall of the food chamber from the rear of the cabinet, and a chilling compartment within the cabinet above the food chamber and having a bottom spaced from the food chamber and resting upon said top guides and provided with air circulation openings communicating with the spaces between the side and back walls of the cabinet and chamber.

7. The device of claim 5, in which the guides between the bottom walls of the cabinet and food chamber are approximately L-shaped in plan, extending toward each other from the sides of the cabinet and thence sharply rearwardly in mutually spaced relation.

8. The device of claim 5 in which the chilling unit therein mentioned comprises a pair of evaporator elements adjacent opposite sides of the cabinet and a freezing chamber in operative association with each of said elements, each such chamber having a forward access opening and walls connected with the cabinet about said opening, whereby to confine within the cabinet convection currents circulating about the chamber and the elements comprising said unit.

9. The device of claim 5 in which the chilling unit comprises a plurality of freezing chambers side by side, and a unitarily functioning evaporating means enveloping said chambers, said chambers having access openings adjacent the

front of said cabinet and walls connected with said cabinet about said openings, whereby to confine convection currents within the cabinet.

10. The structure of claim 5 in which the chilling unit comprises sharp freezing chambers adjacent the sides of the cabinet and an intervening frozen storage chamber and a unitarily functioning evaporator means including portions directly associated with the respective sharp freezing chamber and other portions connecting said first mentioned portions above and below said frozen storage chamber, the respective chambers having access openings adjacent the front of the cabinet and walls connected with the cabinet about said openings whereby to confine within the cabinet convection currents circulating about the chilling unit and food chamber.

11. The combination with a refrigerator cabinet having front door means and side, back, top and bottom walls, of a food chamber connected to said cabinet about said door and having side, back, top and bottom walls spaced from the corresponding walls of the cabinet, a pair of sharp freezing chambers adjacent the sides of the cabinet between the top wall of the food chamber and the top wall of the cabinet, a frozen storage chamber intervening between said sharp freezing chambers, means for supporting the several chambers within the cabinet while accommodating convection currents of air moving down the side walls of the cabinet and up the back wall thereof, and evaporator means comprising portions concentrated adjacent the respective sharp freezing chambers, whereby to accelerate downward air convection, said evaporator portions being in connection across said frozen storage chamber.

12. The device of claim 11 in which said evaporator comprises a tube having successive coils alternately disposed about said sharp freezing chambers and connected by intermediate lengths passing above and below said frozen storage chamber.

GEORGE O. R. LINDGREN.
